Bausch & Lomb Incorporated, Rochester, N.Y., a corporation of New York

Filed Mar. 27, 1961, Ser. No. 64,486

Term of patent 14 years

(Cl. D57—1)

FIG. 1

FIG. 2

FIG. 3

FIG. 1 is a front perspective view of a telescope embodying my new design;

FIG. 2 is a rear perspective view thereof in another operating position. The telescope is continuously tapered for its entire length and is round, and the side of the body portion not shown is substantially like the side shown. The telescope is shown broken away in FIG. 2 for convenience of illustration.

FIG. 3 is a cross-sectional view taken on the line 3—3 of FIG. 2.

I claim:

The ornamental design for a telescope, substantially as shown and described.
